UNITED STATES PATENT OFFICE.

GEORGE AIKEN, OF BELGRADE, MONTANA.

GUARD AND OPERATING MEANS THEREFOR.

Application filed May 19, 1927. Serial No. 192,664.

The invention relates to car-operated guards, and as illustrated, the following uses are given:—Prevention of trespass upon any desired part of a railway, such as at 5 tunnels, bridges, crossings, station and yard entrances, etc.; and closing of mine shafts and elevator shafts, the guard being in each instance opened automatically by approach of the railway car, train, elevator car, mine 10 cage or other car, with whose trackage it is used.

The invention further relates to car-actuated operating means for the guard or for any other means which it is desired to 15 operate by approach of a car or the like, for instance, a visible or audible signal, a switch-throwing mechanism, etc.

For purposes of description, the term "car" 20 will hereinafter be used with the understanding that it applies to all types of cars, cages, trains and the like operable upon trackage.

One object of the invention is to provide 25 an automatic car-controlled guard of rather simple and inexpensive, yet efficient and reliable nature.

A further object is the provision of 30 unique car-actuated operating means for the guard, signal, mechanism, etc. which embodies a unique car-rotated shaft constituting a prime mover.

Other objects are to provide unique means 35 for mounting the above-named shaft, to provide novel means for returning this shaft to normal position after car-affected turning thereof, and to make unique provision for actuating other parts from said shaft.

With the foregoing in view, the invention 40 resides in the novel subject matter hereinafter described and claimed, the description being supplemented by the accompanying drawings.

Fig. 1 is a top plan view of a portion of a 45 railway and the invention associated therewith.

Fig. 2 is a vertical transverse section on line 2—2 of Fig. 1.

Fig. 3 is an enlarged top plan view partly 50 in horizontal section, showing the means for returning the car-operated shaft after turning thereof under the influence of a car.

Figs. 4 and 5 are vertical transverse sec- 55 tional views on lines 4—4 and 5—5 of Fig. 3.

Fig. 6 is a disassembled prospective view 55 of a number of the parts shown in Figs. 3, 4 and 5.

Fig. 7 is a fragmentary top plan view partly in horizontal section, illustrating more particularly the manner of rotatably mounting the car-operated shaft and showing also the operating connection between this shaft and another shaft which carries the guard. 60

Fig. 8 is a fragmentary top plan view further illustrating the manner of rotatably 65 mounting the car-operated shaft.

Fig. 9 is a vertical sectional view on line 9—9 of Fig. 8.

Fig. 10 is an elevation of a portion of the 70 car-operated shaft illustrating the notches formed therein for the reception of one of the shaft bearings.

Fig. 11 is a plan view showing certain seg- 75 mental journal sections which are secured to the car-operated shaft for reception in the shaft bearing.

Fig. 12 is an end elevation of the journal sections shown in Fig. 11.

Fig. 13 is a vertical section on line 13—13 80 of Fig. 9, the shaft however being removed from the bearing.

Fig. 14 is a detail vertical section on line 14—14 of Fig. 7, illustrating the manner of 85 operatively connecting the car-operated shaft with the shaft which carries the guards.

Fig. 15 is a vertical sectional view on line 15—15 of Fig. 14.

Fig. 16 is a fragmentary elevation of the 90 car-operated shaft illustrating the manner in which it is notched to receive a flexible element for transmitting motion to the guard-carrying shaft.

The form of construction selected for il- 95 lustration in the present application, will be hereinafter specifically described, with the understanding that within the scope of the invention as claimed, variations may be made.

Two track rails 17 are shown, secured in 100 the usual way upon ties 18. Transversely alined bearings 19 are disposed under the rails 17 and are secured thereto by suitable clamps 20. In these bearings, a transverse shaft 21 is rotatably mounted, said shaft being provided with rigidly attached guards 22 which are located between the rails 17 and at the outer sides of the latter. These guards normally stand upright as in Figs. 1 and 2, but by the construction hereinafter described, 105 they are automatically swung downwardly upon approach of a car.

23 denotes an elongated shaft parallel with

and spaced inwardly from one of the rails 17. This shaft embodies four circumferentially spaced, longitudinally extending flanges, three of these flanges, denoted at 24, being preferably of uniform width, while the fourth flange 25 is relatively wide. At least this wide flange 25 and the other flanges also in most instances, is given a quarter twist, at one or both ends, so that said end or ends will lie horizontally as shown in Figs. 1, 3 and 6, whereas the major portion of this flange will stand vertically, as seen for instance in Figs. 1 and 5. For purposes of illustration, only one of the horizontally extending ends of the flange 25 is shown, and it is identified at 25^a. This flange end extends toward the adjacent rail 17 in position to be struck by a wheel flange. Thus, due to the twisted or helical formation of the flange 25, the flange of the first wheel engaging it, will turn the entire shaft 23 one-fourth of a revolution. I utilize this turning of the shaft 23 to turn the shaft 21, thereby swinging the guards 22 downwardly and permitting the car to pass. In this connection, it will of course be understood that the shaft 23 is sufficiently long to cause the wheels of the car to hold it in the position to which it has been turned, until the car is past the guards. Then, by means hereinafter described, the shafts 21 and 23 are returned to their normal positions, with the result that the guards 22 again assume the vertical position shown in Fig. 2.

At longitudinally spaced points, the flanges 24-25 of the shaft 23, are formed with groups of circumferentially alined notches 26 which receive bearings 27, employed to rotatably support said shaft. Secured in the angles between these flanges, are segmental journal sections 28 which engage the inner sides of the bearings 27. Each of these bearings is preferably formed of two sections hinged together at 29, and said bearings are secured by bolts 30 to longitudinal supporting bars 31. These bars are provided with integral arms 32 which underlie the adjacent rail 17 and are secured thereto by appropriate clamping means 33. The bolts 30 not only secure the bearings 27 to the bars 31, but hold the sections of said bearings in co-operative relation with each other. Preferably, the bars 31 are formed with longitudinal slots 34 through which these bolts pass, in order that the parts may be relatively positioned in the required manner when the mechanism is being initially installed.

Above the shaft 21, the flanges 24-25 of the shaft 23 are formed with circumferentially alined notches 35. Secured in the angles between these flanges and located at the inner ends of the notches 35, are segmental members 36 which jointly form a cylindrical body. Around this body, a por-

tion of a flexible line 37 is wound as seen most clearly in Figs. 14 and 15, another portion of this line being wound around the shaft 21. Thus, upon car-effected turning of the shaft 23, the line 37 acts as a belt and turns the shaft 21 to effect lowering of the guards 22. Similarly, when shaft 23 is restored to its initial position, shaft 21 and the guards are similarly moved.

38 designates a spring barrel at one end of the shaft 23 and provided with notches 39 which receive the contiguous ends of the flanges 24-25, these flange ends being preferably narrowed somewhat so that they may fit within the barrel. The end of the barrel 38 remote from the notches 39, is rotatably received in a cap 40, which cap contacts with a vertical lug 41 on a longitudinal plate 42. A bolt 43 passes through the lug 41 and through the center of the cap 40 to secure the latter to the former, said cap and lug being provided with inter-engaged sockets 44 and ribs 45 spaced apart around the bolt 43. A torsion spring 46 is disposed in the barrel 38 and has one end 47 passed through a slot 48 of said barrel or otherwise connected with the latter. The other end 49 of the spring is connected with the cap 40, for instance by passing it through an opening 50 in said cap. When the bolt 43 is loosened, the cap 40 may be rotated with respect to the barrel 38, for the purpose of imparting the desired tension to the spring 46. Then, tightening of the bolt 43 will secure the cap tightly against the lug 41 and the interengaging ribs and grooves 45-44, will hold said cap in adjusted position. The spring 46 is thus in readiness to return the shaft 23 and associated parts to their original positions, after movement of said parts has been effected by passage of a car wheel flange onto the flange 25 of the shaft 23. Any desired stop means (not shown) may be employed for limiting the return movement of the parts, under the influence of the spring 46.

The plate 42 is by preference provided with integral arms 51 secured to the adjacent rail 17 by appropriate clamps 52.

While the mechanism engaged by the car wheel is shown arranged on only one end of the shaft 23 for operation by a car approaching in one direction, it is obvious that within the purview of the invention this same mechanism can be arranged on both ends of the shaft for operation thereof by a car approaching from either direction.

By employing the novel construction shown and described or a substantial equivalent thereof, advantageous results are obtainable and hence these structural features are preferably followed. However, within the scope of the invention as claimed, numerous variations may be made, as above stated.

I claim:

1. In an operating means of the class

- described, a shaft parallel with a track rail, said shaft having a plurality of circumferentially spaced longitudinally extending flanges one of which is relatively wide and is of helical form to be engaged by a wheel flange or analogous car part to effect turning of the shaft, said flanges being formed at longitudinally spaced points with circumferentially alined notches, bearings for the shaft surrounding the same within said notches, and segmental journal sections secured in the angles between said flanges and contacting with the inner sides of said bearings. 5
2. In an operating means of the class described, a shaft parallel with a track rail, said shaft having a plurality of circumferentially spaced longitudinally extending flanges one of which is relatively wide and is of helical form to be engaged by a wheel flange or analogous car part to effect turning of the shaft, said flanges being formed at longitudinally spaced points with circumferentially alined notches, bearings for the shaft surrounding the same within said notches, and clamps carrying said bearings for securing them to a track rail. 10
3. In an operating means of the class described, a shaft and means rotatably mounting it parallel with a track rail, said shaft having a plurality of circumferentially spaced longitudinally extending flanges one of which is relatively wide and is of helical form to be engaged by a wheel flange or analogous car part to effect turning of the shaft, said flanges being formed with a group of circumferentially alined notches, and segmental members secured in the angles between said flanges and jointly forming a cylindrical body for imparting movement to another member when the shaft is turned. 15
4. In an operating means of the class described, a shaft and means rotatably mounting it parallel with a track rail, said shaft having a plurality of circumferentially spaced longitudinally extending flanges one of which is relatively wide and is of helical form to be engaged by a wheel flange or analogous car part to effect turning of the shaft, said flanges being formed with a group of circumferentially alined notches, and segmental members secured in the angles between said flanges and jointly forming a cylindrical body for imparting movement to another member when the shaft is turned. 20
5. In an operating means of the class described, a shaft extending longitudinally of a rail and provided with car-engaged means for effecting rotation of said shaft, a cylindrical body on said shaft, a second shaft transverse to the first named shaft and having a cylindrical portion opposite said cylindrical member, and an endless flexible line wound around said cylindrical member and said cylindrical portion to turn the second shaft upon turning of the first named shaft. 25
6. In an operating means of the class described, a shaft having car-engaged means for turning it in one direction, a spring barrel at one end of said shaft connected thereto for rotation therewith, a bearing cap with which the outer end of said barrel is rotatably engaged, a spring in the barrel connected at one end to the latter and at its other end to the cap, said spring being effective to return the barrel and shaft after car-engaged rotation thereof, a stationary support with which said cap contacts, and means normally securing said cap non-rotatably to said support but permitting turning of said cap for tensioning of said spring. 30
7. A structure as specified in claim 6; the last named means consisting of a bolt passing through cap and support and inter-engaged teeth and sockets around said bolt. 35
8. A structure as specified in claim 6; together with a rail-engaging clamp carrying said support. 40

In testimony whereof I have hereunto affixed my signature.

GEORGE AIKEN.
